UNITED STATES PATENT OFFICE

HERMAN SPECTOR, OF BROOKLYN, NEW YORK

DESIGN FOR A DOOR VIEWER

Application filed June 25, 1928. Serial No. 27,278. Term of patent 3½ years.

To all whom it may concern:

Be it known that I, HERMAN SPECTOR, a citizen of the United States, residing in the borough of Brooklyn, county of Kings, in the city and State of New York, have invented a new, original, and ornamental Design for Door Viewers, of which the following is a specification, reference being had to the accompanying drawing, forming part thereof, in which—

Fig. 1 is a front view of a doorviewer, showing my new design; and

Fig. 2 is a side elevation of the same.

I claim:

The ornamental design for a doorviewer as shown.

HERMAN SPECTOR.
